UNITED STATES PATENT OFFICE.

ARTHUR WILLIAM WHITE, OF LONDON, ONTARIO, CANADA.

SEPARATING DEVICE FOR THRASHING MACHINES.

1,402,984.

Specification of Letters Patent. Patented Jan. 10, 1922.

Application filed April 12, 1920. Serial No. 373,336.

To all whom it may concern:

Be it known that I, ARTHUR WILLIAM WHITE, of the city of London, in the county of Middlesex, in the Province of Ontario, 5 Canada, have invented certain new and useful Improvements in Separating Devices for Thrashing Machines, of which the following is the specification.

My invention relates to improvements in 10 separating devices for thrashing machines and the object of the invention is to construct a device of the class described which will separate the grain from the straw. A further object is to construct a device in 15 which the straw will be moved at the required speed to completely clear the same from the thrashing cylinder, such speed increasing until the straw is discharged from the device. A still further object is to provide 20 means for agitating the straw and accentuating the movement thereof while passing over the device.

My invention consists of independent separating decks carrying suitable toothed 25 racks, such decks being preferably inclined to the horizontal, hangers pivotally supporting the lower ends of such decks, lateral stub shafts freely mounted in suitable bearings in the independent decks, rocker arms 30 secured to said stub shafts at their upper ends, independent lateral shafts freely mounted in suitable bearings, the rocker arms of the outer decks suitably secured to one of the lateral shafts and the rocker arms 35 of the intermediate deck suitably secured to the other lateral shaft, depending arms secured to the opposite ends of the respective lateral shafts, a lateral driving shaft, crank wheels mounted on the driving shaft, 40 a suitable power pulley on the driving shaft, connecting rods, each connected at one end to the corresponding crank wheel on the driving shaft and their other ends connected to the depending arms on the respective 45 lateral shafts, and agitators extending longitudinally through said independent decks and suitably secured to the aforesaid stub shafts, all as hereinafter more particularly described and illustrated in the accompanying drawings in which:—

Fig. 1 represents a side elevation of a device constructed according to my invention.

Fig. 2 is an end view thereof.

Fig. 3 is a cross section and

Fig. 4 is a sectional detail of a portion of 55 one of the decks showing the agitators.

Like characters of reference indicate corresponding parts in the different views.

1 are the outer decks and 2 is the intermediate deck. 3 are longitudinal racks suitably mounted on the upper side of the decks 1 and 2, and 4 are inclined lateral slats, suitably separated, and extending between the side members of the decks 1 and 2. 5 are brackets carrying a cross shaft 6, and 7 60 are hanger links pivotally connected at their lower ends to the inner ends of the decks 1 and 2 and at their upper ends to the cross shaft 6.

8 are stub shafts freely mounted in suitable bearings 9 on the inner sides of the side members of the decks 1 and 2, 10 and 11 are lateral shafts rotatably mounted in bearings 12 and 13. 14 are rocker arms suitably secured at their upper ends to the stub 75 shafts 8 of the outer decks 1 and at their lower ends to the shaft 10. 15 is a rocker arm suitably secured at its upper end to the stub shaft 8 of the intermediate deck 2 and at its lower end to the lateral shaft 11. 16 80 is a depending arm secured to the lateral shaft 10, and 17 is a depending arm secured to the opposite end of the shaft 11. 18 is a suitably mounted driving shaft extending laterally of the device and carrying the 85 pulley 19 by means of which the device is driven. 20 and 21 are crank wheels suitably mounted on the ends of the driving shaft 18, and 22 and 23 are connecting rods respectively connected at one end to the 90 crank wheels 20 and 21 and at the other end to the rocker arms 16 and 17.

24 are double agitators of sector shape adapted to extend through longitudinal slots 25 in the decks 1 and 2 on each side 95 of the racks 3. These agitators 24 are suitably secured to the stub shafts 8 of the decks 1 and 2.

The operation of the device is as follows.

Upon the thrashed straw being deposited 100 on the decks 1 and 2, the straw is immediately moved up such decks under action of racks 3 and the alternate reciprocating motion of the decks 1 and 2, the grain being separated from the straw as it moves 105 up these decks and such movement being accentuated by the movement of the agitators 24 until the straw is discharged from

the outer ends of the decks 1 and 2 at a speed preferably double its starting speed. This is achieved by the operation of the decks 1 and 2 and the agitators 24.

- 5 The alternate reciprocatory motion of the outer decks 1 and the intermediate deck 2 is achieved by the positioning of the depending arms 16 and 17 on the shafts 10 and 11, respectively. Thus when through 10 the medium of the connecting rod 22 and the crank wheel 20 the depending arm 16 partially rotates the shaft 10 in one direction with the consequent elevation of the rocker arms 14 and the attached decks 1, 15 the depending arms 17 through the medium of the connecting rod 23 and crank wheel 21 turns the shaft 11 in the reverse direction, consequently lowering the rocker arm 15 and the attached deck 2.
- 20 When the pulley 19 is rotated the connecting rods 22 and 23 oscillate the arms 16 and 17, thus giving an oscillating movement to the rocker arms 14 and 15 connected to the decks 1 and 2. Such oscillatory movement of these rocker arms imparts a peculiar movement to the decks giving them a longitudinal movement in one direction and a corresponding lowering of the outer ends of the decks, and on reciprocating a 25 longitudinal movement in the other direction and an upward movement of the outer ends of the decks.

It will be seen on reference to Fig. 1 of the drawing that the rocker arm 15 of the 30 intermediate deck 2 is so arranged respectively to the rocker arms 14 on the outer decks 1, that the action of such intermediate deck 2 will be alternate to the action to the outer decks 1.

- 40 The agitators 24 being connected to the rotatable stub shafts 8 they will be oscillated by the action of such rocker arms 14 and 15 simultaneously with the lowering and raising of the outer ends of the decks 1 and 2.
- 45 When the outer ends of the decks 1 and 2 are lowered, the agitators 24 will be swung into the position shown in dotted lines in Fig. 4, and when the outer ends of the decks 50 are raised they will be swung into the position shown in full lines. This action of the agitators serves to accentuate the speed of the straw on the decks 1 and 2 as well as separate any grain remaining in the straw by agitating the same.

- 55 The agitators 24 extending through the decks 1 and 2, could be used with a single deck or with decks which do not operate alternately as described above. The essential features of these agitators are that they extend through such deck and are operated in unison with the reciprocatory movement of the same.

From the above description it will be seen that I have devised a simple and effective 60 separating device for thrashing machines

and one that will separate the grain from the straw more effectively than the present separating devices at present in use.

What I claim as my invention is.

1. In a separating device for thrashing machines, independent longitudinally disposed separating decks, longitudinal racks on the upper sides of such decks, suitably separated inclined lateral slats extending across said decks, lateral stub shafts freely mounted in said decks, independent lateral shafts freely mounted below said decks, rocker arms, each secured at one end to the stub shafts in the outer decks and at the other end to the corresponding lateral shaft, 75 a rocker arm suitably secured at one end to the stub shaft of the intermediate deck and at the other end to the other lateral shaft, arms on the opposite ends of the independent lateral shafts and means for oscillating said arms.

2. In a separating device for thrashing machines, independent longitudinally disposed separating decks, hangers pivotally supporting the inner ends of said decks, longitudinal racks on the upper side of such decks, suitably separated inclined lateral slats extending across said decks, lateral stub shafts freely mounted in said decks, independent lateral shafts freely mounted below 90 said decks, rocker arms, each secured at one end to the stub shafts in the outer decks and at the other end to the corresponding lateral shaft, a rocker arm suitably secured at one end to the stub shaft of the intermediate deck and at the other end to the other lateral shaft, 95 arms on the opposite ends of the independent lateral shafts and means for oscillating said arms.

3. In a separating device for thrashing 105 machines, independent longitudinally disposed separating decks, longitudinal racks on the upper side of such decks, suitably separated inclined lateral slats extending across said decks, lateral stub shafts freely mounted in said decks, independent lateral shafts freely mounted below said decks, rocker arms, each secured at one end to the stub shafts in the outer decks and at the other end to the corresponding lateral shaft, 110 a rocker arm suitably secured at one end to the stub shaft of the intermediate deck and at the other end to the other lateral shaft, 115 arms on the opposite ends of the independent lateral shafts, means for oscillating said arms and agitators suitably secured to the stub shafts and extending through longitudinal slots in the decks.

4. In a separating device for thrashing 125 machines, independent longitudinally disposed separating decks, longitudinal racks on the upper side of such decks, suitably separated inclined lateral slats extending across said decks, lateral stub shafts freely mounted in said decks, independent lateral 130

10. In a separating device for thrashing machines, independent longitudinally disposed separating decks, hangers pivotally supporting the inner ends of said decks, longitudinal racks on the upper side of such decks, suitably separated inclined lateral slats extending across said decks, lateral stub shafts freely mounted in said decks, independent lateral shafts freely mounted below said decks, rocker arms, each secured at one end to the stub shafts in the outer decks and at the other end to the corresponding lateral shaft, a rocker arm suitably secured at one end to the stub shaft of the intermediate

deck and at the other end to the other lateral 15 shaft, arms on the opposite ends of the independent lateral shaft, a suitably driven lateral driving shaft rotatably mounted below the decks, crank wheels on said driving shaft, connecting rods, each connected at 20 one end to the corresponding crank wheel on the driving shaft and at the other end to the corresponding arm on the independent lateral shafts, and sector shaped agitators suitably secured to the stub shafts 25 and extending through longitudinal slots in the decks.

ARTHUR WILLIAM WHITE.
